(57) **CLAIM**

The ornamental design for an inhaler, as shown and described.

DESCRIPTION

FIG. 1 is a top front right perspective of an inhaler showing our new design;

FIG. 2 is a front view of the design shown in FIG. 1;

FIG. 3 is a rear view of the design shown in FIG. 1;

FIG. 4 is a right side view of the design shown in FIG. 1, the left side view being a mirror image therefore;

FIG. 5 is a top view of the design shown in FIG. 1; and,

FIG. 6 is a bottom view of the design shown in FIG. 1.

1 Claim, 6 Drawing Sheets
